CLAIM

The ornamental design for a boot for securing a motorcycle tire against rotation, as shown and described.

DESCRIPTION

FIG. 1 is a bottom left rear perspective view of a boot for securing a motorcycle tire against rotation showing my new design;

FIG. 2 is a bottom right rear perspective view thereof;

FIG. 3 is a top plan view thereof;

FIG. 4 is a front elevational view thereof;
FIG. 5 is a right side elevational view thereof, the side
opposite being a mirror image.

FIG. 6 is a bottom plan view thereof; and

FIG. 7 is a rear elevational view thereof.

FIG. 1

FIG. 2

FIG. 3

FIG. 4

FIG. 5

FIG. 6

FIG. 7
